UNITED STATES PATENT OFFICE

1,981,481

FLUID COMPRESSOR

Charles M. Tursky, Philadelphia, Pa.

Application February 9, 1933, Serial No. 655,880

7 Claims. (Cl. 230—177)

This invention relates to apparatus of the general character forming the subject matter of Letters Patent of the United States granted to me and respectively Nos. 1,371,824 dated March 15, 5 1921; 1,478,929 dated December 25, 1923; 1,533- 958 dated April 14, 1925; 1,871,285 dated August 9, 1932; and 1,880,590 dated October 4, 1932; in that a pair of axially aligned rigidly connected pistons are adapted to be reciprocated by a crank member 10 carried between said pistons and fitted to reciprocate transversely to the axis of said pistons and having at its outer end a ball fitted in a socket so as to rotate on an axis at right angles to the axis of said pistons. However, the apparatus disclosed in each of said Letters Patent is characterized by the reciprocation of said pistons within a stationary cylinder, by means of a rotary crank; whereas, my present invention involves a substantial reversal of that arrangement in that 15 it is characterized by the reciprocation of the pistons within a rotary cylinder, by means of a crank which is held stationary.

My present invention is advantageous as compared with the apparatus of said Letters Patent 20 in that the new arrangement permits the moving parts to be continually maintained in balanced relation so that the operation of the apparatus is effected substantially without vibration of the rotary parts and with less expenditure of 25 energy.

My invention includes the various novel features of construction and arrangement hereinafter more definitely specified.

In said drawings, Fig. I is a vertical sectional view of a fluid compressor conveniently embodying my invention, with a cylinder thereof directly connected with the armature shaft of an electric motor for turning it, the motor and the base supporting the same being shown in elevation.

Fig. II is a transverse sectional view of the compressor mechanism shown in Fig. I, taken on the line II, II, in that figure.

Fig. III is a plan view of the crank shaft, having the eccentric ball socket, which is held stationary in the position shown in Fig. I, and the crank pin member having the ball end which is mounted to be turned and oscillated in said socket by the rotation of said cylinder.

In said figures, the base plate 1 is rigidly connected with the bearing bracket 2 for the crank shaft 3 which is rigidly held in said bracket by the nut 4. The stress of said nut 4 upon the shaft 3 also serves to clamp the ball bearing race member 5 in rigid relation with said bearing bracket 2.

Said frame member 1 also supports in rigid relation therewith, the casing of the electric motor 7 which has the armature shaft 8 extending in coaxial relation with said crank shaft 3. Said shaft 8 is detachably rigidly connected, conveniently by the screw 9 and spline 10, with the right hand cover plate 11 of the rotary cylindrical body 12, which is rigidly connected with said plate 11 by a circular series of screws 13. Said rotary cylinder 12 is similarly rigidly connected, 60 by the circular series of screws 14, with the left hand cover plate 15 which carries the ball bearing race member 16 in opposition to said stationary ball race member 5, with the circular series of bearing balls 17 between them in coaxial relation with said crank 3.

Said rotary cylinder 12 has in coaxial relation, at diametrically opposite sides thereof, two similar cylindrical seats 18 in which are respectively fitted similar liner cylinders 19 each having an annular flange 20 respectively bearing against the outer ends of said cylindrical seats 18. Said liner cylinders are respectively held in rigid relation with said cylinder 12 by respective normally stationary but removable screw plugs 22 which bear upon the outer ends of said liner cylinders 19 and clamp them against the outer ends of said seats 18, as shown in Figs. I and II.

Said cylinders 12 are adapted to respectively receive the similar pistons 24 which are rigidly connected by the tubular piston rod 25. Said rod 25 has, intermediate of said pistons 24, the cylindrical bearing 27 with its axis at right angles to the common axis of said pistons and fitted to receive the crank member 28 which has at its outer end the ball 29 shown in Fig. I, fitted in the spherical socket 30 which is rigidly clamped in connection with said crank 3 by the screw collar 31.

The construction and arrangement last above described are such that when the motor 7 is energized to turn the rotary body 12, its cylinders 19 are reciprocated on the pistons 24 held by the crank pin 28 in the socket 30; with a stroke which is, of course, double that of the extent said ball socket is eccentric with respect to the axis of said shaft 3. Said crank pin 28 is turned and oscillated in a vertical plane, upon its ball end 29, and said pistons are rocked upon their common axis by such oscillatory movement of the member 28 while said cylinders are thus reciprocated. Such relative reciprocation of the pistons 24, occasioned by rotation of the cylinder 12, is effective to pump air from the outer atmosphere through one or more ports 33 in said cylinder 100 105 110

cover plate 11, shown in Fig. I, compress it in said liner cylinders 19, and discharge the compressed air through the outlet conduit 34 shown in Fig. I in coaxial relation with said crank 3.

- 5 During the operation of said compressor; the air drawn through the port 33 from the outer atmosphere passes through the chamber 35 between the cover plate 11 and the cylinder 12 and thence to the respective liner cylinders 19 through 10 respective pairs of ports 36 in the cylinder 12 which extend through the side walls of said seats 18 which have annular air passages 37 in communication with ducts 38 formed in the respective screw plugs 22 and leading to the interior 15 of said liner cylinders 19. Said ducts 38 are normally closed by the annular inlet valves 39 which have their outer edges fulcrumed in respective annular recesses in the plugs 22, as indicated in Figs. I and II, but have their inner edges 20 flexed upwardly by the air drawn into the cylinders 19 by the operation of the pistons 24. Said valves 39 serve to prevent the escape of air through said ducts 38 upon reverse movement of said pistons.
- 25 Each of said pistons 24 is provided with a valve 40, which is a flat annular plate adapted to normally close ports 41 in the respective valve casings 42 which are mounted in the outer ends of said pistons, under pressure of springs 43 which encircle axial studs 44 which are stationary in said valve casings 42. It is to be understood that as the pistons 24 are reciprocated by the means above described, they alternately suck the air into their respective liner cylinders 19 and discharge 30 the same through said valve ports 41. Said ports 41 are in communication with the hollow interior of said piston rod 25 when said valves 40 are displaced from their seats by the outward movement of said pistons, and said interior of the 35 rod 25 is in communication with the hollow interior of the crank member 28 through the ports 46 which extend radially through said member 28, as best shown in Fig. II. As shown in Fig. I, the hollow interior of said crank member 28 is in direct communication with the hollow interior of 40 said crank 3 and thence with the conduit 34.

I find it convenient to lubricate the mechanism above described by providing the bracket 2 with the oil inlet 47 which is in communication with the annular groove 48 in said bracket surrounding said crank 3. That groove 48 is in communication with the groove 49 extending longitudinally in the circumference of said crank 3, as shown in Fig. I, and leading into the ball bearing cap 31 which directs the lubricant through the ports 50 55 in the spherical socket 30 in communication with the ducts 51 in the crank pin 28 through which the lubricant is delivered to the bearing 27 by way of the plurality of openings 52 extending from said ducts 51 to the outer surface of said member 28, as shown in Fig. I. As indicated in Fig. II, said ducts are conveniently formed of holes drilled in said crank member 28 parallel with its axis and plugged at their right hand ends, 60 as indicated in Fig. I.

With the proportions shown, the crank pin 28 is turned about one revolution during each four revolutions of the rotary body 12, with the advantageous result that, of course, the valves and other details of construction and arrangement above specified may be otherwise constructed and arranged. Therefore, I do not desire to limit myself to the precise details of construction and arrangement herein set forth, as it is obvious that various modifications may be made therein with- 65

out departing from the essential features of my invention, as defined in the appended claims.

I claim:

1. In a fluid compressor, the combination with a base member; of a crank shaft; means normally holding said crank shaft in stationary position on said base member; a ball socket carried by said crank shaft in eccentric relation with the axis of said shaft; a cylinder mounted to rotate in concentric relation with the axis of said crank shaft; two cylinders in coaxial relation with each other and in diametrical relation with said first cylinder; two pistons rigidly connected by a tubular piston rod and mounted to respectively reciprocate in said axially aligned cylinders; a cylindrical bearing in said piston rod intermediate of said pistons with its axis at right angles to the common axis of said pistons a crank member fitted to reciprocate in said bearing in said rod and having a ball at one end fitted for oscillation in said ball socket; whereby rotation of said first cylinder causes said pistons to reciprocate in said axially aligned cylinders; and valves controlling the passage of air to and from said axially aligned cylinders; whereby air is taken from the outer atmosphere, compressed in, and discharged from said axially aligned cylinders by the reciprocation of said pistons.

2. Apparatus as in claim 1, wherein the axially aligned cylinders are normally held in said first cylinder by respective screw plugs at their outer ends having ducts for the passage of air to said axially aligned cylinders from said first cylinder.

3. Apparatus as in claim 1, including an electric motor having an armature shaft in concentric relation with said first cylinder to rotate the latter upon the axis of said crank shaft and having a ball bearing supporting that cylinder for rotation in concentric relation with said crank shaft.

4. In a fluid compressor, the combination with a base member; of a body mounted to rotate on said base member; a crank member fixed on said base member eccentric to the axis of rotation of said body; a piston; means operatively connecting said piston with said crank member, limiting the freedom of movement of said piston to oscillation upon its own axis; means preventing movement of said piston transversely with respect to its axis; a cylinder in said rotary body engaging said piston and having its axis transverse to that of said body; whereby rotation of said body effects compression of the fluid by reciprocation of said cylinder with respect to said piston; and valve means for automatically controlling the flow of fluid to and from said cylinder in accordance with the movement of the latter.

5. In a fluid compressor, the combination with a base member; of a body mounted to rotate on said base member; a crank member fixed on said base member eccentric to the axis of rotation of said body; a pair of pistons; a rod rigidly connecting said pistons in coaxial relation; means cooperatively connecting said crank member with said piston rod intermediate of said pistons, limiting the freedom of movement of said pistons to oscillation upon their common axis; means preventing movement of said pistons transversely with respect to their axis; a pair of cylinders in said rotary body respectively engaging said pistons and having a common axis transverse to that of said body; whereby rotation of said body effects compression of the fluid by reciprocation of said cylinders with respect to said pistons; and valve means for controlling the flow of fluid to

and from said cylinders in correspondence with the movement of the latter.

6. In a fluid compressor, the combination with a base member; of a body mounted to rotate on said base member; a crank member having a ball socket fixed on said base member, eccentric to the axis of rotation of said body; a piston; a crank pin having a ball end journaled in said socket for transmitting rotary and oscillatory movement from said rotary body to said pin, and limiting the freedom of movement of said piston to oscillation upon its own axis; means preventing movement of said piston transversely with respect to its axis; a cylinder in said rotary body engaging said piston and having its axis transverse to that of said body; and valve means for controlling the flow of fluid to and from said cylinder; whereby rotation of said body effects compression of the fluid by reciprocation of said cylinder with respect to said piston, and rotary and oscillatory movement of said crank pin, the rotary movement of said pin effecting uniform distribution of the wear upon the spherical surfaces of said socket and ball incident to the oscillatory movement of the latter.

7. In a fluid compressor, the combination with

a base member; of a body mounted to rotate on said base member; a stationary crank member having a ball socket fixed on said base member, eccentric to the axis of rotation of said body; a pair of pistons rigidly connected in coaxial relation; a cylindrical bearing between said pistons with its axis extending transversely to the axis of said pistons; a crank pin journaled in said bearing and having a ball end journaled in said socket and limiting the freedom of movement of said pistons to oscillation upon their own axis; means preventing movement of said pistons transversely with respect to their axis; a pair of cylinders in said rotary body respectively engaging said pistons and fixed in coaxial relation upon an axis transverse to said body; and valve means for controlling the flow of fluid to and from said cylinders; whereby rotation of said body effects compression of the fluid by reciprocation of said cylinders with respect to said pistons, and rotary and oscillatory movement of said crank pin, the rotary movement of said pin effecting uniform distribution of the wear upon the spherical surfaces of said socket and ball incident to the oscillatory movement of the latter.
